(57) **CLAIM**

We claim the ornamental design for a scissors holder, as shown and described.

DESCRIPTION

FIG. 1 is a front perspective view of a scissors holder of the new design;

FIG. 2 is a front elevational view of the scissors holder of FIG. 1;

FIG. 3 is a back elevational view of the scissors holder of FIG. 1;

FIG. 4 is a top plan view of the scissors holder of FIG. 1;

FIG. 5 is a bottom plan view of the scissors holder of FIG. 1; and,

FIG. 6 is a right side elevational view of the scissors holder of FIG. 1, the left side elevational view being a mirror image thereof.

The portions of the Figures shown in broken lines are for illustration only and form no part of the claimed design.
